US00D806676S

(12) **United States Design Patent** (10) Patent No.: **US D806,676 S**
(45) Date of Patent: **** Jan. 2, 2018**

(54) **HEADSET FOR COMMUNICATION**

(71) Applicant: **GN Netcom A/S**, Ballerup (DK)
(72) Inventor: **Mads Heje Fuglsang**, Ballerup (DK)
(73) Assignee: **GN Netcom A/S** (DK)
(**) Term: **15 Years**
(21) Appl. No.: **29/580,590**
(22) Filed: **Oct. 11, 2016**

Related U.S. Application Data

(62) Division of application No. 29/514,119, filed on Jan. 8, 2015, now Pat. No. Des. 769,221.

(57) **CLAIM**

The ornamental design for a headset for communication, as shown and described.

DESCRIPTION

FIG. 1 is a perspective view of the embodiment of the headset for communication.

FIG. 2 is a front view thereof.

FIG. 3 is a back view thereof.

FIG. 4 is a left view thereof.

FIG. 5 is a right view thereof.

FIG. 6 is a top view thereof.

FIG. 7 is a bottom view thereof.

FIG. 8 is another perspective view of the embodiment of the headset for communication.

FIG. 9 is a front view thereof.

FIG. 10 is a back view thereof.

FIG. 11 is a left view thereof.

FIG. 12 is a right view thereof.

FIG. 13 is a top view thereof; and,

FIG. 14 is a bottom view thereof.

The features shown in broken lines depict environmental subject matter only and form no part of the claimed design.

1 Claim, 14 Drawing Sheets
